UNITED STATES PATENT OFFICE.

HORACE M. SMITH, OF CHICAGO, ILLINOIS, ASSIGNOR TO LIQUID CARBONIC COMPANY,
OF CHICAGO, ILLINOIS, A CORPORATION OF ILLINOIS.

MACHINE FOR FILLING BOTTLES WITH CHARGED BEVERAGES.

1,419,697.

Specification of Letters Patent. Patented June 13, 1922.

Application filed June 3, 1918. Serial No. 237,839.

To all whom it may concern:

Be it known that I, HORACE M. SMITH, a citizen of the United States, residing at Chicago, in the county of Cook and State 5 of Illinois, have invented certain new and useful Improvements in Machines for Filling Bottles with Charged Beverages, of which the following is a specification.

My invention relates more particularly to 10 that form of filling machine in which a revoluble tank contains the liquid to be filled and is provided with a number of filling valves which receive the bottles to be filled and as the tank revolves admit 15 counterpressure air or gas into the bottles, then admits the liquid with which the bottle is to be filled and finally discharges the filled bottles. The admission of counterpressure gas or air into the bottle before 20 filling the latter is for the purpose of preventing foaming of the liquid as it enters the bottle, particularly as it is charged with gas and is necessarily under gas pressure in the tank. Each filling valve is provided 25 with a filling tube which reaches nearly to the bottom of the bottle, and counterpressure gas is admitted at the mouth or neck of the bottle directly. To provide a smooth filling it is necessary to almost balance by 30 the counterpressure within the bottle, the gas pressure upon the liquid in the tank plus the weight of the column of liquid from the bottom of the bottle to the top of the liquid in the tank. Obviously when the 35 counterpressure in the bottle equals the pressure of the inflowing liquid, made up by the pressure above the liquid and the weight of the column of liquid between the level of the liquid in the tank and the level 40 of the liquid in the bottle, the flow ceases and this is taken advantage of to automatically fill the bottles to a definite height by so regulating the counterpressure that when the liquid reaches the predetermined height 45 in the bottle the counterpressure balances the pressure of the liquid. Prior to my invention this proportioning of the counterpressure to the pressure in the filling tank has been accomplished with more or less 50 success in a variety of ways. The respective pressures have been obtained from different sources each pressure being independently regulated by well-known regulating means. It has also been known to take the gas or air 55 for supplying the tank with pressure and the

bottles with counterpressure from a common source providing for differentiating the pressure by hydrostatic and by purely mechanical means. My present invention relates to means for this purpose of the latter class. It has for its object the provision of a mechanical device which is sensitive and accurate in operation and may be readily adjusted to provide for the filling of bottles to different heights and of bottles 60 of different heights, the regulation of the device being readily effected without stopping the machine or in any manner interfering with its operation.

In the drawings accompanying and forming part of this application I have shown a preferred form of invention and described the same in detail in the following specification. It is to be understood, however, that this specific disclosure is for the purpose 70 of exemplification only and that the scope of the invention is defined in the following claims in which I have endeavored to distinguish it from the prior art so far as known to me, without, however, relinquishing or abandoning any portion or feature thereof.

Referring to the drawings, Fig. 1 is a vertical axial section of the upper portion of a filling machine embodying the preferred form of my invention, parts being shown in elevation; Fig. 2 is a similar section on a somewhat reduced scale of the lower part of the machine; Fig. 3 is a horizontal section on the line 3-3 of Fig. 1; Fig. 4 a similar section on the line 4-4 of Fig. 1, parts being shown in plan; and Fig. 5 is a side elevation of a detail. Each part is identified by the same reference character wherever it occurs throughout the several views.

In a Patent No. 1,275,622 granted to me August 13, 1918, is disclosed a filling machine of the character to which the present invention relates, in which, however, the differential pressure is obtained by hydrostatic means and reference may be made thereto for a further understanding of the general features of the filling machine to which my invention is applied, which is old 100 and well-known in the filling art. Referring more particularly to Fig. 1 the filling tank is shown at 6 and is annular in form and may be supplied with carbonated or soda water, beer or other charged beverage 110

which it is desired to fill into bottles. The tank for supplying the liquid is indicated at 6. This tank may be mounted as usual upon a revolving spider 8 which is journalled upon a standard 9 and revolved by any suitable mechanism common in machines of this character. The supply pipe 7 is connected to a head 10 swiveled upon the pipe 11 extending through the standard 10 and connected at 12 to a pipe leading to the supply of liquid to be filled. Thus the revolving tank is at all times in communication with a source of liquid and by certain devices well-known in the art and which it is not necessary here to describe, is kept filled to a predetermined height therewith.

It is essential to keep the height of the filling liquid at substantially a predetermined level for any run of filling of a given height of bottle or for a desired height in a number of bottles since the level of the liquid in the tank is one of the factors determining the height of the filling.

The tank is annular as shown, the inner wall thereof constituting the wall of a central air chamber 13, which, for the sake of greater capacity, is preferably continued somewhat below the bottom of the tank. The tank and air chamber described are both formed in a single casting by preference. The tank is provided with a cover 14 which is annular in shape and the outer edge thereof is packed at 15 where it joins the outer wall of the tank. This cover is formed with an annular plane section or flange 16 which overlies a horizontal flange 17 extending inward from the edge of the side wall of the air chamber and the joint between the two castings is packed at this point as at 18. Screws 19 secure the two flanges together. At its inner edge the flange on the cover is formed with an upwardly rising nozzle 20 and a downwardly extending skirt 21, which is open at the bottom as at 22. A dome-shaped casting 23 is fitted over the air chamber 13, the bottom of the dome being formed with an outwardly projecting flange 24 which is bolted at 25 to the cover 14. The joint between these two castings is packed as at 26. Except for the valve hereinafter described the interior of the dome communicates through the valve seat and cylindrical skirt with the air chamber 13 and is also in open communication with the tank through the openings 27 formed in the cover 14. Air is supplied to the air chamber 13 through a pipe 28 connected to the center of the bottom thereof. This pipe revolves with the tank and air chamber and is connected to a stationary pipe 29 extending through the head 10 and pipe 11 by means of a packed joint 30. The lower end of pipe 29 is connected by pipe 31 with any suitable source of air or gas 65 at the required pressure.

Thus, but for the valve to be now described, the lower air chamber 13, the dome or upper air chamber 23 and the space above the liquid in the tank would all be supplied with air or gas under the same pressure. 70 The valve seat 20 and skirt 21 are of large diameter and the former receives a valve 32, the central portion 33 of which depends through said skirt and into the lower air chamber 13 and forms a support for a series 75 of weights 34, 34', etc. The central portion or casting 33 of the valve is also formed or provided exteriorly with wings or guides 35, the outer edges of which accurately fit the interior of the cylindrical skirt 21 thus centering and accurately guiding the valve. By reason of the disposition of the center of gravity of the valve well below the valve seat and the provision of the guides there is no tendency of the valve to tip and bind and 85 therefore it readily rises when the pressure in the chamber 13 exceeds that above the valve by the predetermined amount, thus accurately maintaining the difference of pressure below and above the valve. 90

The lower air chamber is connected to the respective filling valves by air tubes 36 for supplying the bottles with counterpressure before the liquid is discharged thereto. As heretofore observed it is desirable or essential to be able to accurately adjust the difference in pressure between the interior of the bottle and the space above the liquid in the tank so that bottles of different heights may be filled and, where desired, the height 100 of the liquid in bottles of the same or different heights predetermined. This I accomplish by adjusting the weight upon the valve 32. For this purpose the interior of the depending portion of the valve is hollow, as 105 above described, and receives the series of weights 34, 34', which rest upon shoulders 37, 37', etc., of progressively increasing diameter from the bottom to the top of the series, the distance between the shoulders being such, with reference to the thickness of the weights 34, 34', etc., supported by the respective shoulders, as to leave spaces between adjacent weights. The weights are axially perforated and a rod 38 extends 110 loosely through the center thereof and is guided at its lower end in a bearing 39 in the valve casting and at its upper end in a bearing 40 formed in a spider 41, the legs of which at their lower ends are connected 115 by an annulus 42 which is bolted or otherwise secured to the valve as by bolts 43. The rod is vertically reciprocable within the bearings and is provided beneath the lowermost weight with a collar or washer 44 120 which, when the rod is raised a definite distance, engages the lowermost weight of the series and raises it from its seat and supports it independently of the valve. A further upward movement of the stem 38 brings the 125 130

lowermost weight in contact with the weight next above it and raises the latter also from its seat, and so on. Thus by adjusting the rod or stem 38 the counterpoises 34, 34' may 5 be picked up in order and the added weight upon the valve regulated at will. In order to adjust the position of the stem 38 I provide it with a cross pin 45 to be engaged by a bifurcated arm 46 secured to a trans- 10 verse shaft 47 which is journalled at 48, 49 in the dome-casting and extends outside the same, there being a packed joint at 50. The outer end of the shaft 49 carries an adjusting handle 51 with a pawl 52 pivoted there- 15 to, said pawl controlled by a handle 53 and engaging a rack sector 54 mounted on the stuffing box 50. The handle is provided with a pointer 55 which co-operates with a dial 56 on the sector. The weights 34, 34', etc., 20 are selected to correspond with the various levels to which it is desired to fill the bottles in connection with which the machine is to be employed. Thus, if the bottles are to be filled as closely as possible to their mouths 25 all the weights are removed from the valve. The latter is of such weight as just to counterbalance a column of liquid extending from a point just below the mouth of a bottle in a filling valve to the normal level of 30 the liquid in the tank. This will then be the difference between the pressure on the liquid in the tank and the pressure in the lower air chamber 13 and therefore when the liquid in the bottle reaches the aforesaid level the 35 pressure of the liquid in the bottle and the counterpressure being equal the liquid will automatically cease to flow. When it is desired to stop the flow of the liquid into the bottle at the next lower level the handle is 40 adjusted to lower the stem and transfer the weight of one of the uppermost counterpoises to the valve. This correspondingly increases the difference between the pressure in the air chamber 13 and in the bottle and 45 that on the liquid in the tank, and consequently the filling ceases when the liquid in the bottle reaches a lower level than that which it would reach were the valve free of all of the added counterpoises, and so on. 50 It is sometimes desirable, however, to fill to some level intermediate those determined by the series of weights and I have provided a micrometer adjustment of the pressure on the valve for this purpose. The upper end 55 of the spider or of the hub 57 thereof is shouldered as at 58 to form a seat for a spring 59, the other end of which abuts against an adjusting screw thumb 60. Said adjusting screw is screwed into a hollow boss 60 61 in the dome and has a stem 62 extending through a perforation in said boss and packed with relation thereto as at 63. The stem is provided with a knurled thumb-piece 64 for rotating the adjusting screw to adjust the same. Obviously by the means just

described, the pressure on the valve can be nicely adjusted to any point intermediate the weights of the counterpoises.

By providing the large air chamber 13 closely adjacent the filling valves which are 70 connected thereto by short air passages I avoid material fluctuations in pressure which might otherwise occur because of the escape of counterpressure air or gas due to the breakage of a bottle or the like. The large 75 valve and valve seat with the weight of the former disposed well below the seat and the provision for guiding the valve secure a very sensitive action of the valve so that the predetermined difference of pressure be- 80 tween the chamber 30 and the space above the liquid in the tank is actively maintained. The construction by which the pressure on the valve may be increased by definite increments enables the machine to be in- 85 stantly changed for filling different bottles or to different levels, the counterpoised weights being chosen with reference to the various sized bottles in ordinary commercial use for the liquids being filled and the 90 micrometer adjustment enables any corrections needed to be accurately made.

I claim:

1. In a machine for filling liquids into bottles comprising a filling tank, a filling 95 nozzle connected to the tank, and adapted to receive the mouth of a bottle, of an upper and a lower air chamber having a division wall provided with a valve seat between them, a connection from the upper chamber 100 to the tank, a connection from the lower chamber to the filling nozzles, a connection for supplying the lower chamber with counterpressure air, and a valve cooperating with the seat and weighted to secure a difference 105 in pressure between the air chambers and means extending through a sealed opening in the wall of the device for regulating the pressure of the valve.

2. In a device of the class described and 110 in combination with the tank, liquid supply and filling nozzles thereof, a pair of communicating air chambers, one of which is connected to the tank and the other to the filling nozzles, a valve controlling the communication between said chambers, and movable means extending through a sealed opening in the walls of the device for regulating the pressure of the valve.

3. In a device of the class described and 120 in combination with the tank, filling nozzles and liquid supply thereof, an air chamber, means for supplying said chamber with air, a connection from said chamber to the filling nozzles, a connection from said chamber to 125 the space above the liquid in the filling tank, a valve for controlling said connection, a series of weights, and means for raising said weights successively from the valve and for depositing them thereon.

4. In a device of the class described, a filling tank, a filling nozzle connected thereto, means for supplying said tank with liquid, an air chamber, a connection from 5 said air chamber to the filling nozzle, means for supplying said air chamber with gas under pressure, a connection from said air chamber to the space above the liquid in the tank, a valve seat in said connection, 10 a valve cooperating with said seat, a series of weights adapted to be deposited seriatim on said valve and to be supported thereon, and means for raising said weights seriatim from said valve and returning them thereto.
- 15 5. In a device of the class described, a filling tank, an upper and a lower air chamber, a diaphragm having a valve seat dividing said chambers, communication from the upper chamber to the tank, filling nozzles carried by the tank, connections from the lower air chamber to the filling valves, a valve cooperating with the seat and comprising a central hollow depending portion; a vertical series of weights within 20 said depending portion, seats for the respective weights therein, a vertically movable rod adapted to pick up the weights successively, and means exterior to the chamber for raising and lowering said rod.
- 25 6. In a device of the class described, a filling tank, an upper and a lower air chamber, a diaphragm having a valve seat dividing said chambers, communication from the upper chamber to the tank, filling nozzles 30 carried by the tank, connections from the lower air chamber to the nozzles, a cylindrical apron depending from said valve seat, a valve coating with said seat and having a central depending portion, guide wings thereon coating with the interior 35 of said apron, a series of weights within the valve, seats on said valve for the respective weights, and means for raising said weights successively, including connections 40 extending to the outside of the chamber for operating the same.
- 45 7. In a device of the class described, a filling tank, an upper and a lower air chamber, a diaphragm having a valve seat dividing said chambers, communication from the 50 upper chamber to the tank, filling nozzles carried by the tank, connections from the lower air chamber to the filling valves, a valve seat 55 having an interior hollow depending portion having successive stepped seats, a series of weights within the valve adapted to connect the respective seats, a rod extending through the series of weights and adapted to raise the same successively, a rock shaft, 60 an arm on the rock shaft connecting said rod for raising the same, and a handle on the exterior of the air chamber for rotating the shaft.
- 70 8. In a device of the class described, a filling tank, an upper and a lower air chamber, a diaphragm having a valve seat dividing said chambers, communication from the upper chamber to the tank, filling nozzles carried by the tank, connections 75 from the lower air chamber to the filling valves, a valve cooperating with said seat and having an interior hollow depending portion having successive stepped seats, a series of weights within the valve adapted 80 to connect the respective seats, a rod extending through the series of weights and adapted to raise the same successively, a rock shaft, an arm on the rock shaft engaging said rod for raising the same, a spring tending to depress said valve, an adjustable abutment against which said spring bears, and means for adjusting said abutment.
- 85 9. In a device of the class described, an annular filling tank having filling nozzles connected thereto, an air chamber the side walls of which constitute the inner walls of a tank, a casting covering said tank and having a valve seat formed integral therewith above said air chamber and communicating therewith, a dome mounted on said casting, there being openings in said casting between said dome and said liquid tank, a valve cooperating with said valve seat and having a depending inner portion adapted 90 to receive counter-poises, and means for successively lifting said counter-poises from the valve and depositing them thereon.

HORACE M. SMITH.
